ADJUSTABLE CASKET TABLE FOR
AUTOMOBILE HEARSE

William Koppe, Brooklyn, N. Y.

Application May 14, 1932. Serial No. 611,415

1 Claim. (Cl. 296—16)

The present invention relates to a casket table for use in automobile hearses and has for its prime object to provide a table which is adjustable so that the casket may be supported in an elevated position in the hearse leaving room thereunder for the flowers and the like.

Another very important object of the invention resides in the provision of an adjustable casket table of this nature which is exceedingly simple 10 in its construction, inexpensive to manufacture and install, easy to manipulate, thoroughly efficient and reliable in use and operation and otherwise well adapted to the purpose for which it is designed.

15 With the above and numerous other objects in view as will appear as the description proceeds, the invention resides in certain novel features of construction, and in the combination and arrangement of parts as will be hereinafter more fully described and claimed.

In the drawings:

Figure 1 is an elevation of a table embodying the features of my invention showing the bottom partition of the hearse in section.

20 Figure 2 is a top plan view of the table.

Figure 3 is a detail section through one of the arms.

Figure 4 is an end elevation of the table.

25 Figure 5 is a view similar to Figure 1 showing another embodiment of the invention, and

Figure 6 is a bottom plan view thereof.

Referring to the drawings in detail and first particularly to Figures 1 to 4 inclusive it will be seen that numeral 5 denotes the bottom of a 30 hearse and numeral 6 the front partition thereof.

Numeral 7 denotes a table on which a casket 8 is adapted to be placed. The casket table 7 is movable from the dotted line position shown in Figure 1 to the full line position shown therein. 35 Numerals 9 denote brackets arranged in two pairs on the bottom 5 and pivotally mounted in each bracket 9 is a tubular arm 10 in which telescopes an arm 11 which is provided with a plurality of openings 12 so that a bolt 14 in the arm

40 10 may be extended therethrough for holding the arm 11 in different adjusted extended positions in respect to the arm 10. The arms 11 are pivoted as at 15 to the side edges of the table 7. A spring 16 is associated with the pivotal connection of each arm 10 with its respective bracket 9 so as to normally hold said arm 10 in a vertical 45 position. A suitable catch 17 is mounted on the table 7 to engage with an eye 18 on the partition 6 for holding the table in its elevated position.

50 It will be readily understood that the table is

5 moved to the dotted line position shown in Figure 1 and the casket placed thereon and then the casket and table are swung upwardly to the elevated position shown in Figure 1. This elevated position may be changed by adjusting the arms 60 11 with respect to the arms 10. When in this elevated position the casket is readily visible in the hearse and the flowers may be placed thereunder.

Now referring to the modification shown in 65 Figures 5 and 6 it will be noted that arms 10' have arms 11' associated therewith in the same manner as arms 10 and 11. In this modification numeral 7' denotes a table. The arms 11', however, are fixed in any suitable manner to shafts 20 on which are cranks 21. Links 22 connect cranks 21 and the rear pair of cranks 21 are connected by a cross bar 23 through which is threaded a threaded rod 24 journaled in a bearing 25 rockable in a bracket 26 suspended from the rear 70 end of the bottom of the hearse so that by turning a crank 27 the arms 10' may be moved from the substantial horizontal dotted line position of Figure 1 to the full line position thereof so as to elevate the casket.

75 It is thought that the construction, operation, utility and advantages of this invention will now be clearly understood without a more detailed description thereof.

The present embodiments of the invention 80 have been described in considerable detail merely for the purposes of exemplification since in actual practice they attain the features of advantage enumerated as desirable in the statement of the invention and the above description.

85 It will be apparent that changes in the details of construction, and in the combination and arrangement of parts may be resorted to without departing from the spirit or scope of the invention as hereinafter claimed or sacrificing any of 90 its advantages.

95 Having thus described my invention, what I claim as new is:

100 In a hearse, the combination with a bottom member having a plurality of slots, of brackets secured to the bottom member adjacent said slots, transverse shafts supported between the brackets, tubular arm members connected at one end with the shafts, rods telescopically engaged with 105 said tubular members, means on the tubular members and engageable with the rods for securing the latter at the desired longitudinal adjustment relative to the tubular members, a table pivoted at its side edges to the free ends of said rods, 110 cranks on the shafts extending downwardly

through said slots, links connecting the cranks in a manner to transmit movement of one shaft to the other, a cross bar connecting the cranks of one shaft, a bracket supported on said bottom, a bearing rockably mounted in said bracket, a rod having an end portion journaled in said bearing

and a threaded portion screw threadedly engaged with the cross bar for rocking said shafts upon turning movement of said threaded rod, and handle means on the free end of said threaded rod for turning it.

80

WILLIAM KOPPE.
